UNITED STATES PATENT OFFICE

CARTER F. HALL, OF BALTIMORE, MARYLAND

COOLING SYSTEM FOR PASSENGER VEHICLES

Application filed June 11, 1929. Serial No. 370,012.

The present invention relates to a cooling system for railway cars and the like, whereby the process of mechanical refrigeration is applied most efficiently in cooling the atmosphere of the car and whereby in connection therewith or independently a continuous supply of cold water uncontaminated by contact with ice and colder than can be obtained by the use of ice is maintained. In the accompanying drawings I have illustrated a cooling apparatus embodying the features of my invention in the preferred form and also showing certain modifications thereof.

In the drawings:

Figure 1 is a front elevation of a stand or casing, enclosing the compressor condenser coil, water cooling compartment and other elements and details of the apparatus.

Figure 2 is a similar view of a modified form of stand or casing.

Figure 3 is a detail of one end of the contact air cooling conduit.

Figure 4 is a front elevation of the cabinet at the top of the stand, shown in Figure 1, with the cover of the cabinet removed.

Figure 5 is an enlarged detail of the cold air supply cooling conduit.

Figure 6 is an elevation of a water cooling stand corresponding to Figures 1, 2 and 4, the front cover being partially removed to show the details.

Figure 7 is an elevation of a railway car of the passenger carrying type equipped with the cooling system of the invention which is shown more or less diagrammatically.

Figure 8 is an enlarged section on the line 8—8 of Figure 7.

Figure 9 is a detail section of the spiral conduit at the inlet end, i. e., where the refrigerant is introduced.

Referring to the drawings by numerals, each of which is used to indicate the same or similar parts in the different figures, the illustration, particularly Figures 1 and 4, shows an upright casing or hollow pedestal 1, upon

which is supported a cooling compartment 2, enclosing the water cooling container shown in the form of a water pipe 3, referred to herein as a stand pipe of comparatively large diameter, the extreme lower end portion of which pipe at 4 forms a tank for cold water to which the cooling effect of the apparatus is directly applied. This pipe 3 in the form of the invention shown is supplied with water from a tank 5, carried by the coach in any convenient location, compressed air and gravity feed forcing the water to points where needed, in this case it being supported in the top of the car 23, from which the pipe 3 depends, extending downwardly into the compartment 2 as already described.

The pedestal or upright casing 1, in the preferred form of the invention, encloses a condenser coil 6, shown at the bottom in Figure 1. This is for cooling the compressed refrigerant, which is preferably sulphur dioxide though any preferred refrigerant may be used. This coil is supplied with compressed refrigerant from the compressor 8 driven by any suitable motor, the coil being cooled in any suitable manner as by means of a draft of air entering in the preferred form, Figure 1, at the bottom from beneath the car through the floor 9 by way of an opening 10, registering with the bottom of the casing 1, the air being led upwardly by a slight vacuum which may be created by connecting the casing 1 by means of a pipe 11 connected to the casing above the compressor with one of the ventilators 12 at the top of the car, or the draft may be created in any suitable manner. It will be easily understood that the casing 1 acts as an air passage and that when the car is in motion the air is sucked out at the ventilators creating a draft through the coil by way of pipe 11. The portion of the system containing the refrigerant is thus hermetically sealed and separated from the interior of the car, avoiding any possibility that in case of accident

or from any other cause, the refrigerant, which is considered harmful, may not escape into the passengers' compartment. In case of leakage, the vapor is carried outside with the cooling air.

Referring now to Figures 1, 4 and 7, the refrigerant which is compressed by the compressor 8 and cooled in the coil 6, is led upwardly from coil 6 by a pipe 14 through the reducing valve 13 to a coil 15, which is shown as inside the water cooling compartment 2 and preferably encircles a brine or holdover tank 16 which, in turn, encloses the lower portion 4 of the cold water pipe which is chilled in a manner to be described furnishing ice water for drinking. This coil 15 is preferably of the helical conduit construction illustrated in detail in Figures 5 and 9, consisting of an outer tubular cylindrical casing 17; a helical shell 18 enclosed within the casing 17 and in contact or nearly in contact therewith providing a helical passage 19 immediately within the casing 17, through its periphery, which, in this instance, is utilized for the refrigerant which is introduced directly thereto from the pipe 14 by way of the fitting 20.

This specially constructed coil 15 in the preferred form also includes a central tubular member 21, within the helical shell 18. While it may be omitted or otherwise utilized in the present instance, this member 21 also contains a refrigerant introduced therein from the pipe 14 by way of the fitting 22, which is connected to it, and the helical shell 18 forms between it and the central tubular member 21 a helical or a similar corrugated passage 24, which is enclosed between the central tubular member 21 described as for carrying the refrigerant and the helical conduit or passage 19 on the outside, also described as carrying the refrigerant, though any of these passages may be otherwise utilized.

The coil 15 is connected at its lower end by fittings 25 and 26 to be described, or in any suitable manner to an air pipe 27, see also Figure 7, which as shown preferably leads along the floor of the car distributing cooled air through a series of pipe connections although it may be located within the car in any suitable manner, this pipe being shown as perforated at 28, though the perforations are not regarded as an essential feature.

The coil 15, as already described, extends upwardly about the brine tank 16 and terminates at the top, as best illustrated in Figure 5 in the inlet air pipe 28, whereby air is introduced either by a fan, suction or pressure from any suitable source as outside the car. At the top the outer helical conduit 19 containing refrigerant is connected by a fitting 30 to a cross or four way fitting 31 and the inner central tubular member 21 is likewise connected thereto by a fitting 32, the return

pipe 34 for the refrigerant from the cooling pipe 33 at the top of the car being likewise connected to said cross fitting 31 by a fitting 35. The remaining connection of said cross fitting 31 is connected by a fitting 36 to a cooling coil 37 within the brine tank 16 and surrounding the standpipe 4 for the cooling water which coil 16 leads the refrigerant to a return pipe 38, which is connected to the suction of the compressor. In this connection it will be understood that brine is used as designating any nonfreezing liquid or solution.

As a means for supplying air, the inlet air pipe 28 to the air cooling coil 15 is connected to the ventilator 12 and provided with a blower or air pump 40, driven by a suitable electric motor, this equipment being diagrammatically indicated in Figure 7. The air from the cooling coil 16 is released from the perforated pipe 27 along the bottom of the car or in any convenient location, perforations 28 being merely illustrative.

To provide further cooling of the atmosphere of the car, refrigerant is led from the pipe 14 by way of a pipe 41 upwardly to the top of the car, being there introduced into any suitable cooling passage, as the outside helical passage 42 of a conduit 43, which may be constructed somewhat after the manner of the conduit 15, the outer casing 17 being preferably omitted. This pipe has an inner conduit 44 which may be used for brine, which begins at the center of the car being plugged at this point as indicated at 45. This brine pipe is also known as a holdover pipe in that it retains the cooling effect after the refrigerant has been released, drawn off or become inactive for any reason.

The refrigerant from the pipe 41 is introduced into the helical passage 42 of the combined conduit 43 in the form of the invention shown at the top center of the car, although this location is not essential, by way of a reducing valve 46 shown at this point, the refrigerant flows in contact with the brine for the full length of the pipe which as shown is half the car length. The return pipe 34 of the coil pipe 33 is connected at the end opposite to the point where the refrigerant is introduced from the reducing valve 46, by way of the fitting 35 to the cross or four way fitting 31. In this fitting the refrigerant from the three passages in the air cooling coil 15 and from the overhead cooling pipe 33 is combined in the water cooling coil 37 already described.

In the form of the invention shown, particularly in Figure 4, provision is made for utilizing the inside of the cooler casing 2, aside from what is occupied by the coils and the water cooler to hold air washing water for cleaning the air introduced by way of the coil 15. To this end the fitting 25 already referred to is shown in the form of a nonreturn valve to prevent the entrance of water into the air

passage of the coil and the fitting 36 is provided in the form of a three way valve which may be turned so as to prevent the cooled air from the coil 15 from passing directly to the 5 pipe 27 and so as to discharge this air from the coil 15 into the wash water indicated by reference character 48. The air thus introduced into the wash water passes upwardly into the air space 47, and hence by way of the 10 bypass 48 back to the pipe 27 at a point beyond the three way valve 26 whence it passes to the perforated portion of the pipe 27 shown in Figure 7. The bypass 48 is also shown as provided with a three way valve 49 above the 15 compartment 2 and an upwardly disposed open elbow 50 connected to the three way valve so that by turning the valve 49 the elbow 50 may be connected to the compartment end 51 of the bypass 48, whereby the elbow 50 20 may be utilized for introducing water into the compartment.

As will be noted in Figure 7, it is proposed to provide a construction corresponding to that shown in Figures 1 and 4 at each end of the car, the cooling pipes 33 and 27 being in two parts or separate units connected to the respective cooling apparatus at the respective ends of the car so that there are two reducing valves 46 at the center and two pipes 27 and 33 extending from each end toward the center, though this arrangement is not essential to the operation of the invention.

Figure 6 shows a water cooling compartment 55 adapted to cooperate with a casing 35 or pedestal 1, as shown in Figure 1, or any suitable pedestal as that shown in Figure 2 to be later described. This compartment is connected to the condenser coil 6 by a pipe 54 and to the compressor by a return pipe 58. This condenser pipe 54 is provided with a 40 pressure reducing valve 56 from which the expanded refrigerant is led directly to a water cooling coil 56 or any suitable means to bring the refrigerant into heat exchanging relation with the water. As shown, the coil 57 encircles the water standpipe 59, being connected at its lower end to the return pipe 58, it being understood that this cooler may be combined in any suitable manner, for example, as shown in Figure 7, with any or all 45 of the air cooling features therein disclosed. This compartment is shown as containing a brine tank 60 in which the coil 57 is immersed, the brine tank in turn surrounding a cold water tank 59. This compartment 55 is further shown as intended to be utilized as an 55 emergency ice chamber to supply the cooled drinking water in case of failure of the refrigerator system for any reason. In this form of the invention, instead of the standpipe 3 being integral and continuous with the cold water tank 4, as shown in Figure 4, there is a separate cold water tank 59 connected to the standpipe 3 by water connection 85 which, 60 in the form of the invention shown, serves as

a cooling coil, it being understood that in the form illustrated the tank 59 is located inside the refrigerator coil 57 and immersed in the brine in the tank 60. This connection 85 as shown extends downwardly from the standpipe 3 through the brine in the tank 60 and is coiled about the tank 59, the coil also being immersed in the brine and extending upwardly. As shown, the upper portion of this water coil 86 is wound about the upper part of the refrigerator coil 57 at 87, the arrangement being preferably of the type shown in Figure 3. This portion of the coil 87, which is wound about the refrigerator coil as shown, is then connected at 88 to the top of the cold water tank 59. It will be understood that in the operation of this form of the invention, the water passing from the pipe 3 to the tank 59 is cooled immediately, the chilled water entering the tank, by its greater specific gravity dropping immediately to the bottom of the tank where it enters the pipe 89 leading to the cold water faucet 65. In this way, the lag incident to the production of cold water when the refrigerator system is first connected up at the time the train is started is overcome and cold water is made instantaneously available.

To overcome the possible objection to the use of mechanical refrigeration in passenger cars on account of the chance that the refrigerant may escape in case of accident, and have a harmful effect on the passengers, the apparatus is shown as provided in each instance in the water cooling compartments 2 and 55, and also in the casing 1 containing the compressor and condenser coil 6, with a fragile or frangible container 62, which may contain an antidote for the refrigerant. Where SO_2 is used as a refrigerant, the bottle may contain ammonia and where ammonia is used as a refrigerant the bottle may contain any suitable acid, volatile or otherwise. This container is normally sealed and is carefully designed of just the right resistance to shock, so that it is broken and the contents released when and normally only when the refrigerating system is punctured.

In Figure 8, which is a section on the line 8-8 of Figure 7, the overhead cooling pipes 33 are shown as supported over a trough 63 to catch the condensed moisture and prevent dripping, and in each instance the water cooler is shown as provided with a water pipe 64 leading from the standpipe 4 or 59 to a spigot 65 arranged in a suitable niche 66 in the compartment cover 67. In Figure 1 there is an aperture 68 for the introduction of used cups which pass downwardly through a pipe 69 to a suitable receptacle not shown and reference character 70 indicates a suitable container for new cups.

Figure 2 shows a slightly modified construction of pedestal which is slightly raised from the floor and the floor 9 being closed be-

neath the pedestal, and air openings 72 being provided at the bottom above the floor. This pedestal is shown as provided with air discharge openings 73 at the top, the air being circulated in any suitable manner, the heat of the condenser coil being regarded as ordinarily sufficient to maintain the circulation.

The operation of the apparatus has been quite fully discussed in connection with the description of the structure. The manner of compressing the refrigerant in the compressor 8 and passing it into the condenser coil 6, where it is cooled and condensed and from whence it is released through a suitable pressure reducing valve 13, flowing in the form of the invention shown in Figures 1 and 5, through the coil 15 surrounding the brine tank 16, going by way of the outer helical passage 19 and the central tubular member 21, to the fitting 31 whence it is returned through the coil 37 which surrounds the cooling water container 4, within the brine tank 16, the coil 37 being immersed in the brine, as has been explained. The drinking water is cooled by the coil 37, the cold air supply being passed through the passage 24 of the coil 15 between the inner and outer streams of refrigerant. In this way chilled water is supplied to the cold water spigot 65 and chilled or cold air to the perforated pipe 27 in the car, the air to be thus cooled and released being propelled in any suitable manner as by means of a blower or pump 40 drawing air from the ventilator. It will be understood that the fitting 36 combines the return refrigerant from the contact cooling pipe 33 and from the inside and outside passages of the coil 15, the refrigerant from all three sources being passed through the coil 37 surrounding the cooling water container 4 as described. The arrangement of coils 15 and 33 is particularly advantageous in that it tends to conserve the refrigerating effect and apply the surplus left from cooling the air to the drinking water. The refrigerant is also carried by the pipe 41 to the contact cooling conduit 33 which is shown in the top of the car, the passage for refrigerant being preferably in a helical form surrounding the central pipe 44 which in this instance is a holdover or brine pipe, the entire conduit 33 serving to cool the air in the car by contact.

The manner of bypassing the cold air supply to be released within the car by way of the three way valve 26 through the washing water 43 and hence back to the air release pipe 27 by way of pipe 48 and three way valve 49, has been fully described, as has also the manner of admitting water by way of the elbow 50 through the three way valve 49.

The manner of supplying air to the condenser coil by drawing it through the floor of the car and discharging it at the ventilator or by means of suction supplied in any suit-

able manner has also been fully discussed, as has also the alternative method of drawing air from the floor of the car or from any suitable source, and permitting it to circulate around the coil and through the casing, being released by the ventilating openings 73 as shown in the modified form, Figure 2.

Figure 1 illustrates a cover 67 adapted to be opened and closed in order to supply ice to be used in case of emergency.

Figure 6 illustrates a water cooler which is like that shown in Figure 4, except that the compartment 55 corresponding to the compartment 2, is used for ice for cooling in an emergency instead of for air washing water, and this water cooler is not directly connected to the air cooling and cool air supplying elements described particularly in connection with Figures 1, 4 and 7.

I have thus described specifically and in detail a water and air cooling apparatus for railway cars and the like, the description being specific and in detail in order that the manner of constructing, operating and using the apparatus may be fully understood. However, the terms herein are used descriptively rather than in a limiting sense, the scope of the invention being defined in the claims.

What I claim as new and desire to secure by Letters Patent is:

1. The combination in a cooling system for railway cars and the like of a cooling compartment, a hollow pedestal therefor containing a condenser coil for the refrigerant and a compressor, the pedestal having an opening below the coil for the introduction of cooling air and a pipe above the coil for leading air therefrom to a ventilating outlet of the car, a water cooling container enclosed in the compartment and a cooling coil for expanded refrigerant in heat exchanging relation with the water container.

2. The combination in a cooling system for railway cars and the like of a cooling compartment, a hollow pedestal therefor containing a condenser coil for the refrigerant, the pedestal having an opening below the coil for the introduction of cooling air and a pipe above the coil for leading air therefrom to a ventilating outlet of the car, a water cooling container enclosed in the compartment and a cooling coil for expanded refrigerant in heat exchanging relation with the water container.

3. The combination in a water cooling system for passenger vehicles, a hollow upright, a condenser coil for refrigerant in the upright, a compressor, a container for drinking water, a cooling coil for expanded refrigerant in heating exchanging relation with the water container, the hollow upright serving as an air conduit and having an opening at the bottom for admitting air from beneath the vehicle and a pipe leading from the con-

tainer having suitable exhausting means for maintaining the circulation.

4. The combination in a cooling system for passenger cars of a water cooling container, a compressor and a condenser for refrigerant, a cooling coil for refrigerant in heat exchanging relation to the container, an air cooling pipe for cooling the air consumed in the vehicle, a passage for the refrigerant in heat exchanging relation with said air cooling pipe, said passage for the refrigerant being connected to said cooling coil whereby the said refrigerant used in cooling the air is later utilized on its return to the compressor for cooling the water supply.

5. The combination in a cooling system for passenger vehicles of a compressor and a condenser for the refrigerant, a cooling coil having means for bringing the refrigerant and air in close contact throughout a substantial portion of the length of the coil, means for introducing air into the coil, pipes for discharging air into the car and means for washing the air prior to its discharge and after it is passed through the coil.

6. The combination in an apparatus for cooling water for passenger vehicles, of a cooling compartment, an air conduit beneath the compartment passing to the floor of the vehicle, a condenser coil for refrigerant therein, the conduit having an opening below the coil for admitting air and an opening above the coil for discharging air, a water cooling container in the compartment and a coil for expanded refrigerant connected to the condenser coil and in heat exchanging relation with the water container, the compartment being adapted to contain ice as an emergency cooler.

7. The combination in a mechanical refrigerating system for passenger vehicles of a motor, a compressor, a condenser coil for refrigerant and a refrigerating coil, a frangible container for antidote to the refrigerant in close association and enclosed with part of said elements of the cooling system.

8. The combination in a cooling system for passenger vehicles of a water cooling container, a motor, a compressor and a condenser for refrigerant, an air cooling chamber, a cooling coil in heat exchanging relation with the water container, means for passing the refrigerant in contact with an air cooling coil surrounding the container and means for passing air cooled by said coil through said air cooling chamber and a pipe system with means for discharging the cold air therethrough and distributing the same through the vehicle.

9. The combination in a cooling system for passenger vehicles of a motor, a compressor and a condenser for refrigerant with means for cooling the condenser, means for cooling the air in the vehicle comprising two concentric conduits and a helical conduit between

said concentric conduits to form a helical passage for the refrigerant in contact with the walls of one of said conduits, said conduit also including a helical passage for air in contact with said helical passage for refrigerant and a central passage for the refrigerant.

10. The combination in a water cooling system for railway cars and the like of a cooling compartment, a hollow upright beneath the compartment containing a condenser coil for the refrigerant, a compressor, a motor, an opening at the base of the upright opening below the coil for the introduction of cooling air and means above the coil for leading the air therefrom, a water cooling container in the compartment, means connected to the condenser for bringing the refrigerant in heat exchanging relation with the water in the container.

11. The combination in a water cooling system for railway cars and the like of a cooling compartment, a hollow upright beneath the compartment containing a condenser coil for the refrigerant, a motor, a compressor, an opening at the base of the upright, an opening below the coil for the introduction of cooling air and means above the coil for leading the air therefrom, a water cooling container in the compartment, means connected to the condenser for bringing the refrigerant in heat exchanging relation with the water in the container, said means including a brine container surrounding the water container and containing said means connected to the condenser.

12. The combination in a water cooling system for railway cars and the like of a cooling compartment, a hollow upright beneath the compartment containing a condenser coil for the refrigerant, a compressor, a motor, an opening at the base of the upright having an opening below the coil and compressor for the introduction of cooling air and means above the coil for leading the air therefrom, a water cooling container in the compartment, means connected to the condenser for bringing the refrigerant in heat exchanging relation with the water in the container, the compartment also including a space which can be used for emergency ice.

13. The combination in a water cooling system for railway cars and the like of a cooling compartment, a hollow upright beneath the compartment containing a condenser coil for the refrigerant, a compressor, a motor, the upright having an opening below the coil near the floor for the introduction of cooling air and means above the coil for leading the air therefrom, a water cooling container in the compartment, means connected to the condenser for bringing the refrigerant in heat exchanging relation with the water in the container, and a conduit for cooling the air in the car, said conduit including a passage for

refrigerant, means connecting said passage to the condenser and to said water cooling means.

14. The combination in a water cooling system, a hollow upright, a condenser coil for refrigerant in the upright, a compressor, a motor, a container for drinking water above the upright, a cooling container for expanded refrigerant in heat exchanging relation with the water container, a hold over container for said liquid container and cooling container, the hollow upright serving as an air conduit and having an opening at the bottom below the condenser coil and compressor for admitting air therefrom to a ventilating outlet above the air inlet.

15. The combination in a water cooling system, a hollow upright, a condenser coil for refrigerant in the upright, a compressor, a container for drinking water above the upright, a cooling container for expanded refrigerant in heat exchanging relation with the water container, the hollow upright serving as an air conduit and having an opening at the bottom below the condenser coil motor, and compressor for admitting air to a ventilating outlet above the air inlet.

16. The combination in a cooling system, a hollow upright, a condenser coil, a compressor, and a motor, in the upright a cooling compartment integral with the upright, an opening in said cooling compartment to be opened and closed, a hold-over container, a cooling device for receiving condensed fluid from said condenser, and compressor, in heat exchanging relation with said hold-over container, heat insulating means surrounding said cooling compartment, hold-over, and said cooling device, in the compartment, driving means for said motor, and compressor, an opening below the motor, condenser, and compressor, for admitting air to a ventilating outlet above the condenser, motor and compressor.

17. The combination in a cooling system, a hollow upright, a condenser coil for refrigerant, a compressor, and a motor in the upright, a cooling compartment integral with the upright, an opening in said cooling compartment to be opened, and closed, a cooling device for receiving condensed fluid from said condenser and compressor, in said cooling compartment, heat insulating means around said cooling compartment, and said cooling device, driving means for said motor, and compressor, an opening below the motor, condenser and compressor for admitting air, a ventilating outlet above the condenser, motor and compressor.

18. The combination in a cooling system, a hollow upright, a motor, a compressor, and a condenser in the upright, a cooling compartment integral with the upright, an opening in the cooling compartment to be opened and closed, a liquid reservoir, in the cooling compartment, means for cooling the liquid

comprising two spiral tubes surrounding said liquid reservoir and forming a passage for the refrigerant and a passage for the liquid to be cooled in heat exchanging relation with said liquid reservoir, said last named passage connecting with said liquid reservoir, a holdover in heat exchanging relation with said liquid reservoir, and said tubes in said cooling compartment, said cooling compartment having heat insulating means, an opening at the base of the upright below the motor, compressor and condenser for admitting air to a ventilating air outlet above said air inlet.

19. The combination in a cooling system, a hollow upright, a motor, a compressor, and a condenser in the upright, a cooling compartment integral with the upright, an opening in the cooling compartment to be opened and closed, a liquid reservoir, in the cooling compartment, means for cooling the liquid comprising two spiral tubes surrounding said liquid reservoir and forming a passage for the refrigerant and a passage for the liquid to be cooled in heat exchanging relation with said liquid reservoir, said last named passage connecting with said liquid reservoir in said cooling compartment, said cooling compartment having heat insulating means, an opening at the base of the upright below the motor, compressor and condenser for admitting air to a ventilating air inlet above said air inlet.

20. The combination in an apparatus for cooling water for passenger vehicles of a cooling compartment, an air conduit beneath the compartment, a condenser coil, for refrigerant therein said conduit, passing to the floor of the vehicle, the same having an opening below the coil for admitting air and an opening above the coil for discharging it, a water cooling container in the compartment, and a coil for expanded refrigerant surrounding the water cooling container connected to the condenser coil.

21. The combination in a cooling system for passenger vehicle, a hollow upright enclosing a compressor, motor, and a condenser for a refrigerant, said hollow upright having air inlet below the motor, compressor, and condenser and having an air outlet above the air inlet motor, compressor, and condenser means for inducing a flow of air from said inlet to said air outlet, associated with said upright a chamber having an air inlet, and an air outlet, enclosing a refrigerant evaporator, a conduit connected to said chamber for discharging air within the passenger vehicle, means for inducing a flow of air through said chamber and conduit, means for cleaning said air, associated means of supplying and discharging a volatile refrigerant from said evaporator, to said condenser, and compressor.

22. The combination in a water cooling system, a hollow upright, a condenser coil

for refrigerant in the upright, a compressor, a motor, a container for drinking water, a cooling container for an expanded refrigerant in heat exchanging relation with the water container, said water container and said cooling container for expanded refrigerant having heat insulated means to insulate them from the condenser motor, and compressor, associated means for supplying and discharging a volatile refrigerant from said cooling container to said compressor and condenser, means for supplying and discharging liquid to said water container, a faucet connected to said liquid container, a drain pipe attached to casing for liquid reservoir, the hollow upright serving as an air conduit and having an opening at the bottom below the condenser coil motor and compressor for admitting air therefrom to a ventilating outlet above the air inlet.

23. The combination in a water cooling system, a hollow upright, a condenser coil for refrigerant in the upright, a compressor, a motor, a container for drinking water, associated with the upright, a cooling container for expanded refrigerant in heat exchanging relation and surrounding said water container, the cooling compartment being adapted to receive ice or other refrigerant, said cooling compartment, liquid container and cooling container for expanded refrigerant having heat insulating means insulating them from said motor, compressor, and condenser, means for supplying and discharging liquid from said liquid container, the hollow upright serving as an air conduit, and having an opening below the condenser, motor, and compressor, for admitting air to a ventilating outlet above the air inlet, said cooling compartment having an opening to be opened and closed.

24. The combination in a water cooling system, a hollow upright, a condenser, a compressor, and a motor in the upright, a liquid container, associated within the upright, an evaporator for expanded refrigerant in heat exchanging relation with said liquid container, a spiral conduit in contact therewith for the liquid to be cooled, a spiral passage for the refrigerant in contact with the spiral passage for the liquid to be cooled, heat insulating material surrounding said cooling means and liquid container within said hollow upright, means for passing a cooling fluid in thermal contact with said container, said condenser coil receiving compressed fluid from said compressor, means for driving said motor and compressor, an opening at the base of the upright below the condenser, motor, and compressor, for admitting air to a ventilating outlet above the air inlet.

25. The combination in a water cooling system, a hollow upright, a condenser coil in the upright, a compressor, a motor, a reser-

voir for drinking water integral with the upright, a cooling container for expanding refrigerant in heat exchanging relation with said reservoir and a spiral conduit in contact therewith for the liquid to be cooled, means for passing and withdrawing liquid through said spiral conduit, said cooling container and said spiral conduit surrounding said liquid reservoir, heat insulating material surrounding said cooling container, spiral passage, and liquid reservoir, communicating means between said compressor, evaporator and cooling container, means for supplying and withdrawing liquid to said liquid reservoir, an opening below the motor, condenser and compressor for admitting cooling air, to a ventilating outlet above said air inlet.

26. The combination in a water cooling system, a hollow upright, a compressor, a motor and condenser, in the upright, a water cooling container in the upright having a spiral coil in heat exchanging relation for expanded refrigerant with the cooling container, means for withdrawing and supplying liquid through said spiral coil, means for supplying liquid and withdrawing liquid from said liquid reservoir, a compressor, a motor driving said compressor, means for forming a substantially fluid tight casing having included therein a motor and compressor, means for passing a cooling fluid in thermal contact with said condenser, said condenser receiving compressed fluid from said compressor, means for driving said motor and compressor, said spiral coil receiving condensed fluid from said condenser and compressor, heat insulating means within the upright surrounding said cooling device, an opening at the base of the upright below the condenser, motor, and compressor for admitting air to a ventilating outlet above the air inlet.

27. The combination in a water cooling system comprising a motor, condenser, a compressor within a hollow upright, an evaporator, a liquid container, heat insulating material above said hollow upright surrounding said evaporator and liquid container, said hollow upright having an opening at the bottom below the condenser coil, motor, and compressor for admitting air thereto to a ventilating outlet above the air inlet.

28. The combination in an apparatus for cooling air and water for passenger vehicles, comprising an air cooling compartment, an evaporator, a liquid container, a brine container, means for compressing a refrigerant, cooling the refrigerant, and forming a closed circuit for the refrigerant and for returning the refrigerant to be recompressed, and means for bringing the refrigerant, air, liquid and brine in heat exchanging relation with the evaporator.

29. The combination in an apparatus for

cooling air and water for passenger vehicles, comprising an air cooling compartment, an evaporator, a liquid container, means for compressing a refrigerant, expanding the refrigerant, cooling the refrigerant, to form a closed circuit for the refrigerant and for returning the refrigerant to be recompressed, having means for bringing the refrigerant, air, and liquid in heat exchanging relation with the evaporator, means for washing the air prior to its discharge into the car.

Signed by me at Baltimore, Maryland, this 27th day of May, 1929.
